Term of patent 14 years

(Cl. D61—1)

FIG. 1

FIG. 2

FIG. 3

FIG. 4

FIGURE 1 is a front and left side perspective view of a photographic copying machine showing my new design; FIGURE 2 is an elevational view of the right side thereof;

FIGURE 3 is a top plan view thereof; and

FIGURE 4 is a rear elevational view of the photographic copying machine.

The dominant features of my design for a photographic copying machine reside in the portions shown in full lines.

I claim:

The ornamental design for a photographic copying machine, substantially as shown and described.
